COMPUTER OUTPUT MICROFILMER

Homer A. Smith and Wilbur D. Robinson, both of 400 N.
Plymouth Ave., Rochester, N.Y. 14650

Filed Apr. 29, 1968, Ser. No. 11,662

Term of patent 14 years

Int. Cl. D14—02

U.S. Cl. D26—5

FIG. I

FIG.2

FIG.3

FIGURE 1 is a top right front perspective view of a computer output microfilmer showing our new design;

FIGURE 2 is a low left rear perspective view showing the left side, rear, and bottom thereof; and

FIGURE 3 is a view similar to FIGURE 1 but with the upper doors open showing the internal arrangement of the components.

We claim:

The ornamental design for a computer output microfilmer, as shown and described.
